UNITED STATES PATENT OFFICE

ALBERT N. CRAMER, OF TOLEDO, OHIO, ASSIGNOR TO OWENS-ILLINOIS GLASS COMPANY, OF TOLEDO, OHIO, A CORPORATION OF OHIO

GLASSWARE-ANNEALING LEER

Application filed May 11, 1928. Serial No. 276,834.

The present invention relates to improvements in glassware annealing leers and more especially that type in which ware is carried through an annealing chamber in which it is desired to obtain a certain temperature gradient predetermined by the type of ware to be annealed.

In the usual leer of the type above referred to, the leer roof is spaced above the ware conveyor a sufficient distance to accommodate ware of maximum height. With leers of this type, the annealing of small ware involves a considerable waste of heat and not infrequently comparatively poor annealing of the ware. In this connection, it is obvious that the most effective heating medium in the heating zone rises quite rapidly to the upper areas of the annealing chamber to a plane considerably above that occupied by relatively small ware. Accordingly, the ware may be insufficiently heated in the heating zone at the front end of the leer, or if sufficiently heated, has involved consumption of an excessive volume of fuel.

According to the present invention, there is provided means whereby the most effective portions of the heating medium in the heating zone may be held in the areas occupied by the ware, regardless of its height, to thereby insure proper heating of the ware. To this end, a partition is disposed horizontally in the annealing chamber in proximity to the upper ends of the ware being annealed to prevent rapid rise of the annealing medium to a plane in which it will not affect the ware.

Another object is to provide an annealing leer with means whereby the heating of a great space above the ware being annealed is obviated, with the result that fuel consumption is materially decreased.

A further object is to provide means for obtaining the above results and so arrange said means that manual adjustment thereof is readily obtainable to meet the demands of different types of ware being annealed.

Other objects will be apparent hereinafter. In the accompanying drawings:

Fig. 1 is a fragmentary side elevation of a leer embodying my invention.

Fig. 2 is a fragmentary side elevation in

detail with parts in section illustrating the adjustment means employed.

Fig. 3 is a fragmentary detail perspective view with parts in section, illustrating the mode of operation and adjustment of the invention.

Fig. 4 is a detail sectional view with parts in elevation.

Fig. 5 is a fragmentary perspective view illustrating a part of the adjusting mechanism.

Fig. 6 is a detail perspective view of a slightly modified form of partition.

In the drawings, the leer is shown as comprising a tunnel including a stationary roof 10 connecting the upper edges of side walls 11. These walls and roof are held in assembled relation by a suitable framework 12 (Fig. 1). The tunnel may be supported above the floor on pillars 13 or the like, which, according to the present disclosure, carry rolls 14 over which the lower reach 15 of the ware conveyor 16 runs. This conveyor 16 is trained over suitable rolls 17 at the front end of the leer and extends rearwardly through the tunnel 18 wherein the ware is arranged while being annealed. Suitable driving means (not shown) imparts continuous or intermittent movement to the conveyor 16 for conveying the ware through the leer. The ware supporting reach of the conveyor moves in a fixed horizontal plane over a floor 19 (Fig. 4).

A vertically adjustable partition 20 is arranged in the annealing chamber above the ware conveyor 16 and is suspended from a longitudinal series of transverse rock shafts 21 by rock arms 22 (Figs. 3 and 4). This partition 20 is of a length substantially corresponding to the zones in which the ware is initially heated and cooled beyond the critical point, the reasons for which will be apparent presently. Obviously, the length may be varied as circumstances demand.

The partition, according to the present disclosure, comprises a series of angle iron bars 25 extending longitudinally of the leer and connected together at their ends by transverse angle iron bars 26, the latter being riveted or otherwise suitably secured to hinges 27 carried at the lower ends of the rock arms 22.

The vertical flange of this transverse bar 26 is connected through hinges 27 to an end plate or wall 29 which is secured to the rock shaft and rock arms and closes the space defined by 5 said shaft and arms. Metal plates 30 are riveted or otherwise fixed to the under side of the horizontal flanges of the angle iron frame members 25 and extend to points in proximity to the side walls 11 of the leer.

10 The partition carries along its side edges means to seal the space between the partition and side walls of the leer. As shown, this means comprises flexible strips 31 of non-inflammable material such as, for example, asbestos. These strips have wiping engagement 15 with the inner faces of the leer side walls 11, permitting free vertical movement of the partition when necessary and preventing passage of the annealing medium upwardly into 20 the space above said partition. Sealing strips 32 are secured to the outer edges of the rock arms 22 whereby the spaces between the rock arms and side walls of the leer are closed to thereby prevent or at least minimize entry of 25 the annealing medium into the space above the partition.

The area through which the ware actually passes is preferably heated by convection heat currents created by a heating unit (not 30 shown) at the front end of the leer, while the area above the metal partition 30 is heated by conduction heat currents through said partition.

In supporting the partition 30 for vertical 35 adjustment in the annealing chamber, a series of longitudinally spaced transverse pairs of rock arms 22 are employed, the number of pairs obviously being determined by the length of the partition to be supported. A 40 transverse sheet or partition plate 29 connects each pair of rock arms 22 so that the space above the horizontal partition is divided into several independent chambers.

The transverse rock shafts 21 are journaled 45 in bearings 35 in the side walls 11 of the leer and corresponding ends of these shafts extend outwardly beyond one side wall and have fixed thereto depending rock arms 36 which are pivoted at their lower ends to a connector rod 37 (Figs. 1 and 3). The length of the connector rod 37 and the spaced relation between the lower ends of the rock arms 36 are variable by means of turn buckles 38 located between each pair of rock arms 36. One of the 50 arms 36, preferably the one adjacent the operating mechanism to be described, is provided with a pointer 39 which cooperates with graduations 40 to indicate the elevation of the partition. Thus, the partition may be accurately set as required by the particular type 55 of ware being annealed.

The partition adjusting mechanism (Figs. 2 and 5), according to the present disclosure, comprises a rod 41 connected through a compensating link 42 to the pointer carrying rock

arm 36, said rod having its free end portion screw threaded and extending through a housing 43 enclosing a worm gear 44 which is threaded on said rod 41. A worm 45 (Fig. 5) is enclosed in the housing 43 and has driving engagement with said worm gear 44. A manually rotatable hand wheel 46 is fixed to one end of a shaft 47 which carries the worm 45. By rotating the hand wheel 46, the rod 41 will be moved longitudinally to either raise or lower the partition relative to the ware conveyor 16. The housing 43 is formed with an extension 48 on one side, said extension being pivoted to a transverse hinge pin 49 in a bracket 50. Thus, with variations in the angular positions of the rock arms 36, the rod 41 and operating mechanism therefor will readily correspondingly change its angular position insuring smooth operation of the devices.

In operation, assuming that the ware to be annealed is rather small, the hand wheel 46 will be rotated in a direction to lower the partition to an elevation at which it is only slightly spaced above the ware passing therebeneath on the conveyor 16. With the partition arranged at this elevation, the most effective portions of the annealing medium are held in the lower areas of the leer tunnel in contact with the ware. Thus, the necessity for heating the entire cross sectional area of the leer tunnel is avoided and accordingly a material saving in fuel consumption is effected.

In addition, by holding the most effective portions of the annealing medium in direct contact with the ware, more perfect annealing is obtained than in leers of ordinary construction. Obviously, by proper adjustment of the partition, equally satisfactory results are obtainable irrespective of the size 95 or type of ware being annealed. By dividing the space above the partition into a series of individual chambers spaced longitudinally of the leer, rearward movement of heat in the front end of the space above the partition to the rear areas of said space is avoided. Obviously, without these intermediate partitions, difficulty would be experienced in obtaining the desired temperature gradient, in that, as above stated, the heat at the forward 100 end would move rearwardly and raise the temperature in the areas at the other end, whereas these back areas should be comparatively cool.

In Fig. 6, the horizontal partition plate 30 is shown provided with a series of apertures 51 by which a greater or less degree of upward movement of the annealing medium into the upper chambers is permitted. Thus, the temperatures above and below the partition are substantially the same but rapid upward movement of the heating medium away from the ware is obviated.

Modifications may be resorted to within the spirit and scope of the appended claims.

What I claim is:

1. In a glassware annealing leer, an annealing chamber, a ware conveyor extending therethrough, a partition extending longitudinally and transversely of at least a portion of the chamber and spaced above the conveyor, a series of longitudinally spaced transverse rock shafts journaled in the side walls of the leer, rock arms interconnecting the shafts and partition, and means to adjust the angular positions of the rock arms and thereby correspondingly change the elevation of the partition relative to the conveyor. 5 70
2. In a glassware annealing leer, an annealing chamber, a ware conveyor extending therethrough, a partition extending longitudinally and transversely of at least a portion of the chamber and spaced above the conveyor, a series of longitudinally spaced transverse rock shafts journaled in the side walls of the leer, rock arms interconnecting the shafts and partition, means to adjust the angular positions of the rock arms and thereby correspondingly change the elevation of the partition relative to the conveyor, and partition plates closing the space between transverse pairs of rock arms to divide the area above the partition into a longitudinal series of chambers. 15 80
3. In a glassware annealing leer, an annealing chamber, a ware conveyor extending therethrough, a partition extending longitudinally and transversely of at least a portion of the chamber and spaced above the conveyor, a series of longitudinally spaced transverse rock shafts journaled in the side walls of the leer, rock arms interconnecting the shafts and partition, means to adjust the angular positions of the rock arms and thereby correspondingly change the elevation of the partition relative to the conveyor, interconnected rock arms secured to corresponding ends of the rock shafts outside of the leer, and an adjusting device operatively connected to one of the last named rock arms for imparting a rocking movement to all of said arms to thereby vary the spaced relation between the partition and conveyor. 25 90
4. In a glassware annealing leer, an annealing chamber, a ware conveyor extending therethrough, a partition extending longitudinally and transversely of at least a portion of the chamber and spaced above the conveyor, a series of longitudinally spaced transverse rock shafts journaled in the side walls of the leer, rock arms interconnecting the shafts and partition, means to adjust the angular positions of the rock arms and thereby correspondingly change the elevation of the partition relative to the conveyor, interconnected rock arms secured to corresponding ends of the rock shafts outside of the leer, an adjusting device operatively connected to one of the last named rock arms for imparting a rocking movement to all of 30 100
5. In a glassware annealing leer, an annealing chamber, a ware conveyor extending therethrough, a horizontal partition arranged in the chamber above the conveyor, flexible sealing strips arranged along the longitudinal margins of the partition for contact with the side walls of the leer, means including a series of rock arms to effect relative vertical adjustment between the conveyor and partition, and flexible sealing strips carried by said arms and contacting with the leer walls. 35 105
6. In a glassware annealing leer, an annealing chamber, a ware conveyor extending therethrough, a horizontal partition arranged in the chamber above the conveyor, flexible sealing strips arranged along the longitudinal margins of the partition for contact with the side walls of the leer, means to effect relative vertical adjustment between the conveyor and partition, a series of longitudinally spaced transverse rock shafts journaled in the side walls of the leer, rock arms supporting the partition from said rock shafts, transverse plates closing the ends of the space above the partition, and flexible sealing strips on the outer margins of the rock arms having wiping engagement with the side walls of the leer. 40 110
7. In a glassware annealing leer, an annealing chamber, a ware conveyor extending therethrough, a horizontal partition arranged in the chamber above the conveyor, flexible sealing strips arranged along the longitudinal margins of the partition for contact with the side walls of the leer, means to effect relative vertical adjustment between the conveyor and partition, a series of longitudinally spaced transverse rock shafts journaled in the side walls of the leer, rock arms supporting the partition from said rock shafts, transverse plates closing the ends of the space above the partition, flexible sealing strips on the outer margins of the rock arms having wiping engagement with the side walls of the leer, and hinge connection between the partition and the adjacent horizontal margins of said plates. 45 115
